SEAM LOCK FOR STOVE PIPES

John J. Holub, Chicago, Ill.

Application September 14, 1934, Serial No. 743,994

4 Claims. (Cl. 137—75.1)

My present invention pertains to sheet-metal pipes such as are employed in connection with stoves, furnaces, and other structures, for conducting air, smoke and similar gaseous elements from the heating structure to different locations, and also for leading air back to the furnace when the latter is of the warm-air or re-circulating type.

In fabricating conductor pipes it has been the practice to utilize a rectangular blank of sheet-metal that is rolled into cylindrical form or terete and to provide an intercalated or interlocked seam to join the overlapped or meeting edge portions of the blank. This seam has usually been made by forming shoulders and off-set portions along the longitudinal proximate edges of the blank, and then forming reverse bends intermediate the widths of the off-set portions. Thus the free edge portions or flaps that extend from the bends to the adjacent edges of the blank may be interlocked by hooking each with the other, and when assembled the interhooked elements prevent relative circumferential movement in a single direction;— that is, in a direction that would enlarge the diameter of the finished pipe. Attempts have also been made to prevent relative circumferential movement in the direction reverse to that just mentioned, which movement would tend to unlock and release the interlocked or interhooked flaps of the seam. Most of such attempts have had inherent defects in the structures with the result that they have met with uncertain success.

With the structure disclosed herein I have provided a very positive lock that successfully prevents attempts to move the joined or seamed edges in both circumferential directions, except after a distinct distortion of the pipe as when it is desired to unlock the same. Such distortion is necessary for the purpose of both unlocking and in assembling the structure.

My present lock-seam for stove-pipes is novel in construction, it is dependable in performing its functions; it is easy to manipulate either for locking or unlocking; and it is economical to manufacture, so that it may be sold to the consumer for a reasonable retail price. The foregoing are some of the objects and advantages which I have had in mind in devising my improved lock-seam, and others will be apparent to persons skilled in the art after my structure is understood.

I prefer to accomplish the numerous objects, and to practice my invention, in substantially the manner hereinafter described and as more particularly pointed out in the claims. Reference is made to the accompanying drawing that forms a part of this specification, in which drawing,

Fig. 1 is a fragmentary view in elevation showing my improved lock-seam applied to a metal pipe.

Fig. 2 is a transverse horizontal section thereof taken on line 2—2 of Fig. 1, looking in the direction of the arrows and drawn to an exaggerated scale for clearness.

Fig. 3 is another transverse horizontal section taken on line 3—3 of Fig. 1, looking in the direction of the arrows, and drawn to the same scale as Fig. 2.

Fig. 4 is a plan of an edge portion of the metal blank showing the arrangement of the parts forming one side of the lock-seam.

Fig. 5 is another view of the structure shown in Fig. 4, disclosing the first fold or reverse bend to provide the lock-seam.

Fig. 6 shows the two proximate edges of a pipe body or blank after the second or final reverse bend has been made, the respective left-hand and right-hand edge portions of the body being disposed in the relative position for the initial step of the assembly or interhooking of the lock seam.

The pipe consists of an initially flat rectangular body or blank 10 of sheet-metal of the desired gage, that is rolled or otherwise formed so that the completed pipe is of cylindric shape or terete in cross-section. To complete the pipe the proximate edges of the blank are brought together and interlocked by means of an intercalated seam.

Both longitudinal edges of the body 10 have several elongated notches 11 cut therein, and said notches are spaced from each other to provide a plurality of laterally projecting tongues 12, 13, along the respective edges. The upper edges of the respective tongues are tapered or oblique as indicated at 12a, 13a, so that said tongues are shortened along their outer longitudinal edges, the purpose of which will be hereinafter more fully explained.

For convenience, one longitudinal edge only, the left-hand edge, of the blank is shown in Figs. 4 and 5, but it will be understood that the other edge, the right-hand edge, is provided with similar notches and tongues.

Each of these edges of the blank is given a reverse bend along the plane of dot-and-dash line x that passes lengthwise through the tongues. This reverse bend disposes the free ends of the left-hand edge tongues on the outside of the body, while the bend at the opposite (right-hand) edge positions the free edges of its tongues on the other or inside the body.

A second reverse bend is made in the body of the blank back of the notches along the plane of dot-and-dash line y at each longitudinal edge portion so that the free edges of the tongues 13 are folded inside or disposed within the respec-

tive seam flaps. An S or Z bend is also made in the body of the blank back of the already folded portions and near each of the proximate edges. These S-bends provide shoulders or 5 abutments 14 extending longitudinally of the body alongside and slightly spaced from the folded edges formed by the reverse bends x. Said S-bends also provide off-set portions that extend longitudinally along each edge portion of 10 the body and are wide enough so that the two reversely bent sections are disposed or included in said off-set portions.

It will be seen that the double, reverse bends x and y provides seam flaps A and B that extend 15 along the respective longitudinal edges of the body on the opposite faces thereof, so that they may be interengaged or hooked with each other when the longitudinal edges are assembled with each other as seen in Fig. 3. The tongues 12 and 20 13 at each edge are folded inside their respective flaps A and B, and said tongues are disposed normally opposite each other so that they may be interengaged or hooked with each other when the structure has been assembled.

25 In assembling the structure to interfit or interlock the seam, the blank or body is held in cylindrical form with the seam edges toward each other and the body is then warped slightly as schematically shown in Fig. 6. This disposes the 30 respective corners of the body the one above the other, and also disposes tongues 12 and 13 of the flap B opposite the recesses or notches 11 of the flap A. The proximate edges are then overlapped with each other and the flap B, with its 35 tongues, is inserted or hooked under flap A by a circumferential relative movement so that the edge at the piece at the right in Fig. 6 will be between the shoulder 14 and the folded portions of the tongues of the left piece shown in said 40 figure and it will abut the shoulder of said left piece. The same relation is true in connection with the edge of the left piece (Fig. 6) which will have its extreme edge abut the shoulder of the right piece.

45 After this initial engagement is made the respective portions are moved or slid longitudinally in opposite directions as indicated by arrows in Fig. 6, which movement will cause the tongues 12 and 13 of one seam edge to insert themselves in interlocked or interhooked relation with the 50 corresponding tongues of the other seam edge as shown in enlarged detail in Fig. 2.

An effective and dependable lock is thus provided that positively prevents relative movement 55 of the respective edges in either direction circumferentially of the completed pipe. Any tendency to contract the pipe is prevented by the outer bends y of the flaps abutting the adjacent shoulders z and also by the tongues 12-13 engaging inside the bends x, while tendency to expand the pipe is prevented by the interhooked disposition of the respective parts which causes bends x to engage inside the bends y. However, the seam may be readily unlocked and separated 60 by simply reversing the before-mentioned steps. The oblique portions 13a provide the notches with outer portions or mouths that are wider than their inner portions to facilitate the entry of the projecting portions of the opposite 65 tongues, and such oblique portions also tend to guide the adjacent end edges of the flaps when entering the notches. It is to be noted that the reverse bends x lie in intermediate portions of

the tongues so that the portions of the tongues that are back of the bends form projections along the free edges of the respective flaps with the notches or recesses 11 between them, and it is these projections on one part of the seam that are inserted into the notches 11 of the opposite part of the seam when the assembly is being made.

5 It will be appreciated that instrumentalities other than those specifically disclosed herein 10 may be employed in carrying out my invention, and I therefore desire it understood that modifications and changes may be made in the structure herein described and shown without departing from the principles involved, and such 15 modifications and changes are contemplated within the scope of the appended claims.

What I claim is:

1. A sheet metal structure comprising two metal edges joined together, both edges being 20 bent back on themselves to provide flaps forming an interlocking joint permitting longitudinal movement along the joint, each flap edge carrying an extension turned inwardly to lie substantially parallel with the sheet body in the space 25 between the body of the sheet and its flap said extensions being also adapted to interlock when the sheets are longitudinally moved with respect to each other so that said extensions are overlapping and slide into interlocking position. 30

2. A sheet metal structure comprising two metal edges joined together, both edges being bent back on themselves to provide flaps forming an interlocking joint permitting longitudinal movement along the joint, each flap edge carrying 35 spaced extensions turned inwardly to lie substantially parallel with the sheet body in the space between the body of the sheet and its flap, the respective extensions being also adapted to interlock when the sheets are longitudinally 40 moved with respect to each other so that said extensions are overlapping and slide into interlocking position.

3. A stove-pipe comprising a sheet of metal 45 bent into tubular form to present two meeting edges forming a seam, both meeting edges of the sheet being bent back on themselves to provide flaps forming an interlocking joint permitting longitudinal movement along the joint, each edge flap carrying an extension turned inwardly to lie 50 substantially parallel with the sheet body in the space between the body of the sheet and its flap, said extensions being also adapted to interlock when the edges of the sheet are longitudinally moved with respect to each other so that said 55 extensions are overlapping and slide into interlocking position.

4. A stove-pipe comprising a sheet of metal 60 bent into tubular form to present two meeting edges forming a seam, both meeting edges of the sheet being bent back on themselves to provide flaps forming an interlocking joint permitting longitudinal movement along the joint, each edge flap carrying spaced extensions turned inwardly to lie substantially parallel with the 65 sheet body in the space between the body of the sheet and its flap, the respective extensions being also adapted to interlock when the edges of the sheet are longitudinally moved with respect to each other so that said extensions are 70 overlapping and slide into interlocking position.
